UNITED STATES PATENT OFFICE.

LOUIS J. RHEIN AND RANDOLPH A. REHRAUER, OF TWO RIVERS, WISCONSIN.

RETAINING MEANS FOR HAIRPINS, COMBS, AND THE LIKE.

1,397,904.

Specification of Letters Patent.

Patented Nov. 22, 1921.

Application filed March 30, 1918. Serial No. 225,832.

To all whom it may concern:

Be it known that we, LOUIS J. RHEIN and RANDOLPH A. REHRAUER, citizens of the United States, and residents of Two Rivers, in the county of Manitowoc and State of Wisconsin, have invented certain new and useful Improvements in Retaining Means for Hairpins, Combs, and the like; and we do hereby declare that the following is a full, clear, and exact description thereof.

Our invention relates to improvements in means for preventing the accidental withdrawal of hair pins, combs and the like from the wearer's hair, the principal object of the device being to prevent the loss of articles of this general nature. The means is so constructed, however, that the hair pin, comb or the like may be readily withdrawn at the will of the user. It is also an object of the invention to provide means on hair pins, combs or the like for retaining the massed arrangement of the hair of the user.

A further object is to provide a simple and efficient article of this character which can be inexpensively manufactured and marketed at approximately the cost of the average hair pin or comb of similar quality.

With these and other objects in view, the invention resides in the novel features of construction, combination and arrangement of parts which will be hereinafter more particularly described and claimed, and shown in the drawing wherein:

Figure 1 represents a hair pin of celluloid, rubber or similar material having our invention incorporated therewith.

Fig. 2 is an elevational view of a wire hair pin also formed with the invention.

Fig. 3 is a view similar to Fig. 1 showing the modified form of the invention.

Fig. 4 is a wire hair pin provided with said modified form of the invention, and

Fig. 5 is an elevational view of a comb of conventional design provided with our improved retaining means.

Referring more particularly to Fig. 1, the numeral 1 denotes a shell or bone hair pin, which form of hair pin is usually constructed of celluloid, amberoid or similar material. As is usual in articles of this character the same consists of a pair of legs 2 and 3 which are connected together as at 4 at one end. Such hair pins are substantially inverted U-shape and the connecting portion 55 of the legs is resilient to permit the latter

to readily move toward and away from each other.

The present invention consists in adding an inwardly extending projection on each leg, said projections in the present form being arcuate. The projection 5 which is formed on the leg 2 has its outer end spaced a greater distance from the free end of said leg than the distance between the outer end of the other projection 6 and the similar end 65 of its leg 3.

Owing to this disposition of the projections, it will be seen that they are offset with respect to each other and in close proximity. Furthermore such relationship 70 of the parts permits the innermost portion of each projection to extend beyond and to be intersected by, a plane extending longitudinally of the legs and equidistant from each as indicated by the line A B.

The hair pin illustrated in Fig. 2 is substantially the same as that hereinbefore described except that it is formed of wire. Such hair pin includes substantially parallel legs 2^a and 3^a connected together at 80 one end as at 4^a. The projections 5^a and 6^a are formed respectively on the legs 2^a and 3^a, and the former is spaced inwardly of the latter as in the first described form.

Referring now to the Fig. 3 wherein it 85 will be seen that a hair pin of the character illustrated in Fig. 1 is shown, the same comprising a pair of legs 2^b and 3^b, the major portions of the same being substantially parallel and resiliently connected together as 90 at 4^b. The retaining means in this instance consists of a pair of projections 5^b and 6^b formed respectively on the legs 2^b and 3^b. These projections serve the same purpose as the projections in the other two forms, the 95 principal difference being that the passageway between the adjacent portions being more tortuous. This is provided by bending the intermediate part of each projection outwardly as at 7. Thus, inasmuch as 100 one projection is disposed outwardly of the other, the outermost end portion of the projection 5^b is positioned in the depression provided by the bending outwardly of the central part of the projection 6^b. Similarly 105 the innermost portion of the last mentioned projection is disposed in the depression 7 of the other projection 5^b.

A wire hair pin constructed in the manner of the hair pin just described is illus- 110

trated in Fig. 4. In this instance instead of adding projections to the legs 2^c and 3^c, the intermediate portions of the same are bent inwardly toward each other to provide co-
5 operating projections 5^c and 6^c. These pro-
jections have their intermediate parts bent outwardly to procure the tortuous passage-
way referred to in the last paragraph in con-
nection with the form depicted in Fig. 3.

10 Our invention is also applicable to combs as well as hair pins, as will appear from the examination of Fig. 5 in which 8 denotes a comb of conventional design having a plurality of teeth 9 and 10. The outermost 15 teeth 9 each have an inwardly extending arcuate projection 11 formed thereon for co-operation with similar arcuate projections 12. Such projections serve the same purpose as the similar parts of the hair pins, one being positioned outwardly of the other. Although the comb is shown with a retaining means at each end, it is obvious that the same may be constructed with only one such means, or with more than two, the number 25 of the same as well as their location being immaterial. In any case whether the invention is applied to a comb or to a hair pin, it is preferable that the teeth or legs, as the case may be, be resilient.

30 The operation is the same in all instances and is briefly as follows: For example a hair pin is forced into the wearer's hair, such movement springing the legs apart slightly to permit the strands of hair to 35 pass between the projections. After the hair pin is inserted as far as necessary or

desirable, the legs obvious move together to their normal position to dispose the projections in close proximity. The hair is thus retained in the relatively closed space between said projections and the connected portion of the legs. The strands of hair will be so retained until the hair pin is pulled outwardly by the wearer, and there is slight danger of the same accidentally 45 working out and becoming lost.

We claim as our invention.

A hairpin comprising a pair of legs resiliently connected together at one end, an arcuate projection formed on each leg, the arcuate projection of one leg being closer to the free end of its leg than the arcuate projection of the other leg is from its corresponding end, the arc of said projections being struck on a relatively long radius, the middle portion of each projection being bent laterally away from the longitudinal center of the pin, the inner end portion of the curve of the first mentioned projection and the lateral bend thereof being engaged with, or in close proximity to, the outer end portion of the curve of the second mentioned projection and the lateral bend thereof to provide a relatively long entrance throat and a tortuous passageway therebetween.

In testimony that we claim the foregoing we have hereunto set our hands at Two Rivers, in the county of Manitowoc, and State of Wisconsin.

LOUIS J. RHEIN.
RANDOLPH A. REHRAUER.
